United States Patent Office

Des. 181,622
Patented Dec. 10, 1957

181,622

CASING FOR CASH REGISTER OR THE LIKE

Robert E. Boyden, San Gabriel, and Newton S. Leichter,
Los Angeles, Calif., assignors to Clary Corporation,
San Gabriel, Calif., a corporation of California

Application May 28, 1956, Serial No. 41,668

Term of patent 14 years

(Cl. D64—11)

FIG. 1

FIG. 3

Fig. 1 is a perspective view of a casing for a cash register or the like, showing our new design.

Fig. 2 is a side elevational view thereof, and

Fig. 3 is a plan view thereof.

The essential features of our design reside in the parts shown in full lines.

We claim:

The ornamental design for a casing for a cash register or the like, substantially as shown and described.
